UNITED STATES PATENT OFFICE.

ASHBY H. LEE, OF ST. LOUIS, MISSOURI.

VENDING MACHINE.

Application filed January 19, 1925. Serial No. 3,431.

The object of my device is to make a vending machine to be used particularly for liquids such as liquid soap. A further object is to devise a vending machine made 5 operative by the insertion of a coin, such as a penny; one that will be inoperative unless a coin or slug of exact previously determined dimension is inserted. A still further object is to make a machine of the type described, of few and simple parts that lend themselves readily to multiple production and that may be easily assembled.

With these and other objects in view, my invention has relation to certain novel features of construction and arrangement of parts as will be hereinafter more fully described, pointed out in the claims, and illustrated in the drawing, in which,

Fig. 1 is a side elevation of my device.

Fig. 2 is a front elevation.

Fig. 3 is a vertical section on the line 3—3 of Fig. 2.

Fig. 4 is an enlarged fragmental sectional elevation on the line 4—4 of Fig. 1.

Fig. 5 is an elevation of the coin operating mechanism.

Fig. 6 is an end elevation of the liquid measuring valve with the container and delivery spout shown fragmentally.

Fig. 7 is a rear elevation of the coin operated clutch.

Numeral 8 designates the casing for my device which is secured to the wall board 9 in any conventional manner.

The casing 8 provides an upper space 10 for the reception of the liquid container 11, and a lower space 12 for a coin receptacle 12^a and my valve mechanism 14, together with its delivery spout. The liquid container 11 is supported in the casing 8 on the side wall brackets 13, the valve mechanism 14 being secured to the bottom of the liquid container 11 and hanging in the lower space 12.

Numeral 14^a designates a delivery spout in fluid communication with the valve mechanism 14 at one end, and passing into the delivery hole 15 in the casing 8 at the other end. In the front wall of the casing 8, immediately in front of the valve mechanism 14 is formed the coin slot 15^a, into which the coin 16 is inserted in order to make the valve mechanism 14 operate when the handle 16^a, which is secured to the shaft 16^b, which passes through one of the side walls of the casing 8 into engagement with the

valve mechanism 14, is turned. The coin 16, after having performed its function, drops into the lower space 12, or coin receptacle 12^a. The valve mechanism 14 is so constructed that the valve well 17 is normally filled with liquid and in fluid communication with the liquid container 11 by means of a conduit 18.

The construction of the valve mechanism 65 is the following:—It is secured to the bottom of the liquid container 11 by means of screws 19 passing through the journal plate 20, and by means of the delivery spout 14^a and the conduit 18. The conduit 18 is preferably soldered to the bottom of the liquid container 11. The cylindrical housing 21 is formed integrally with the delivery spout 14^a and the conduit spout 18, establishing fluid communication between them there- 75 through. A frusto-conical hole 22 passes through the cylindrical housing 21 from face to face. The frusto-conical shell 23, the walls of which form the valve well 17, is positioned in the hole 22. A hole 24 is 80 formed in the shell 23, establishing fluid communication between the valve well 17 and the exterior of the shell. Numeral 25 designates a relatively smaller air hole like- 85 wise establishing air communication between the valve well 17 and the exterior of the shell. Numeral 26 designates a small air hole establishing air communication between the exterior of the shell 23 and the hole 22. When the shell 23 is in the position shown 90 in Fig. 3 in solid lines, the liquid may flow from the liquid container 11 into the well 17 through the conduit 18 and the hole 24. When the shell 23 is rotated a portion of a turn to the left until the hole 24 is in regis- 95 tration with the mouth of the spout 14^a and the hole 25 is in registration with the hole 26, the contents of the well 17 will be permitted to flow gravitationally through the spout 14^a. The fluid communication between the liquid 100 container 11 and the valve well 17 is broken during this time. By these means the contents of the well 17 may be delivered to the spout 14^a by a turn of the shell 23.

A disk 27 having lugs 28 and 29 formed 105 on its periphery is cast integrally with a shaft 30 of lesser diameter, which shaft is formed integrally, centrally, on the shell 23. On the shaft 30 a pin 31 is formed to which at one end is secured the coiled spring 32, 110 the other end of which is secured to the bottom of the liquid container by the screw

33. The coiled spring 32 maintains the shell 23 normally in the position shown by solid lines in Fig. 3, that is, in the position for filling the well 17.

5 Numeral 34 designates a shaft to which is keyed the disk 35; formed integrally with the disk 35 are formed the shoulder 36 and the shoulder 37 of lesser diameter than the shoulder 36, and the left end of the shaft 34 10 (Fig. 4) is recessed longitudinally and a small coiled spring is secured therein and extends outwardly a short distance beyond the end of the shaft. A drift pin 38 passes through holes in the shaft 16^b and the hole 39 in the shaft 34, thereby connecting selectively the shaft 34 with the shaft 16^b. The shaft 16^b passes through a hole in the side wall of the casing 8. The shoulder 37 is journaled in a hole in the journal plate 20. It will be seen that when the handle 16^a is turned, 15 the purpose of the structure thus far described and to be further described hereafter is to enable the shell 23 to be rotated when the handle 16^a is turned, but only when a coin is inserted (by means to be subsequently described). The handle may be turned, together with the disk 35 without the insertion of a coin, but in that event 20 there will be no engagement between the disk 35 and the disk 27. The engagement of these two disks is necessary in order to rotate the shell 23, and this engagement is only brought about by the insertion of a coin and the turning of the handle 16^a. The coin acts as a means for actuating a clutch or dog (to be subsequently described).

In order to hold the disk 35 in its normal position, a coiled spring 40 is positioned 40 over the shoulder 36, between the disk 35 and the journal plate 20, the one end being secured to the shoulder 36 and the other to the journal plate 20. The disk 35 has a peripheral flange 41 formed integrally therewith, in which flange is formed the arcuated coin receiving recess 42 and the chordal slot 43. In the space between the peripheral flange 41 and the central shaft are formed the following elements, the upper surfaces 45 of all of which are in the same plane with the plane of the flange 41. A bent lever 44 fulcrumed at 45 has a knob 46 formed thereon, which extends through a slot in the arcuated coin recess 42. At the end of the lever 44 a dog 47 is rotatively secured, its other end extending into the chordal slot 43. It will be seen that when the knob 46 is moved inwardly that the dog 47 will be moved to the left and its end made to protrude beyond the chordal slot 43. In order to normally hold the dog 47 in such a position that it will not protrude beyond the periphery of the disk 35, a knob 49 is formed on its lower surface, and a leaf spring 50 secured to the 55 disk 35 at one end contacts the knob 49 at

its other. When a coin 16 is inserted in the coin receiving recess 42, the dog 47 will be made to protrude beyond the periphery of the disk 35.

In the center of the disk 27 is formed a recess 51 into which fits the spring at the end of the shaft 34. In assembling, the disk 27 and the disk 35 come in sliding contact with each other. In order to secure the engagement of these two disks, the dog 47 may be pressed to its extended position so that its end meets the lug 28. Then the disk 35 will carry the disk 27 with it. The coin initially causes the dog 47 to engage the lug 28, and the frictional engagement between the dog 47 and the lug continues the contact as long as the handle 16^a is turned, and this is sufficient to cause the flow of the liquid out of the spout. The handle movement is limited to a small part of a full turn. When the handle is released, it assumes its normal position by rotating in the opposite direction, the dog 47 resumes its normal position, the engagement between the disk 27 and the disk 35 is broken, and the shell 23 resumes its normal position.

In order to limit the rotational movement of the shell 23, a metal strip 51^a is secured by means of the screws 52 on the end of the shell 23. This strip extends beyond the periphery of the shell and engages lugs 53 and 54 on the housing 21.

The progress of the coin through the device is the following. It enters the coin slot 15^a and passes into the coin receiving recess 42. When the handle 16^a is turned, the coin is pressed against the top of the recess and against a projection 53 and then downwardly against the knob 46, thereby causing the lever 44 to function, as previously described. The coin continues and falls into the lower space 12. It will be seen that by exact designing and the shaping of the coin receiving recess 42 that only a coin having the exact dimensions of the genuine coin 110 will actuate the device.

The spring 32 serves to return the valve 23 and disk 27 to starting position after a manipulation to deliver the contents of the well 17, and the metal strip 15^a and stop 53 115 limit the movement of the valve so that the opening 24 normally registers with the conduit 18. The spring 40 serves to return the disk 35 to starting position and the stop 55, carried by disk 35 and lug 29 on the disk 27 120 limits the movement of the disk 35 so that the coin recess 42 normally registers with the coin slot 15^a.

Obviously so long as the dog 47 resides wholly within the disk 35, manipulation of the handle 16^a will have no effect upon the valve 23.

Assuming the parts are in their normal positions, as just described; the well 17 filled and a coin inserted as shown by solid lines 125

in Fig. 5 and by dotted lines in Fig. 6, and the handle 16^a and disk 35 turned clockwise, it will be noted that the coin will be engaged by the projection 53 and forced to the left 5 (in Fig. 6) and thus move the lever 44 and dog 47 to the left a distance to cause the dog to project beyond the periphery of the disk 35 where it will engage the lug 28 and hence carry the disk 27 and valve along with it, so 10 that the opening 24 in the valve will be brought to register with the delivery spout 14^a. A release of the handle permits the springs 32 and 40, stop 55 and lug 29, and metal strip 51^a and stop 53 to function as 15 recited.

What I claim and mean to secure by Letters Patent is:

In a device of the character described, a 20 valve mechanism, a disk having lugs formed thereon, secured to said valve mechanism, a

second disk secured to a shaft, the end of which is rotatively secured in a recess formed in the center of said first disk, means for rotating said shaft, said second disk having a coin slot formed therein, a lever rotatively secured at one end positioned therein, a dog rotatively secured at one end to the free end of said lever, said dog being slidably positioned in a slot in said disk, the slot, lever, and dog being so positioned relative to each other that when a coin is inserted in the coin slot of said disk and said shaft is turned, said lever will be oscillated and said dog moved laterally to protrude beyond the periphery of said second disk and engage 35 one of the lugs on said first disk, thereby turning said first disk and said valve mechanism.

In testimony whereof I affix my signature.

ASHBY H. LEE.
